UNITED STATES PATENT OFFICE.

PAUL GUMBINNER, OF NEW YORK, N. Y.

DESIGN FOR PLAITED FABRIC.

SPECIFICATION forming part of Design No. 28,051, dated December 14, 1897.

Application filed September 30, 1897. Serial No. 653,649. Term of patent 3½ years.

To all whom it may concern:

Be it known that I, PAUL GUMBINNER, a citizen of the United States, residing at New York city, in the county and State of New York, have invented and produced a new and original Design for Plaited Fabric, of which the following is a specification, reference being had to the accompanying drawings, forming a part thereof, in which—

10 Figure 1 is a plan view of the obverse side of the fabric, the central portion being broken away; and Fig. 2 is a plan view of the reverse side of the fabric broken away similarly to Fig. 1.

15 The features of the design consist of a fabric presenting upon its obverse side series of intersecting plaited or fluted panels A, the panels being in pairs, and the plaited or fluted lines a of each pair of panels connect at an-

gles to one another, and the plaited or fluted lines of each pair of panels are in angular conjunction with corresponding lines upon an adjacent panel of an adjoining pair. 20

Upon the reverse side of the fabric the same characteristics are presented as shown upon 25 the obverse side, except that where the panels join longitudinal ribs B appear, having a serpentine configuration. A minor feature of the design consists in the scalloped upper and lower edges of the fabric. 30

I claim—

The design for plaited fabric, herein shown and described.

PAUL GUMBINNER.
